INVENTOR

JOSEPH WIENER

By

A. Hanisich Jr.

ATTORNEY

UNITED STATES PATENT OFFICE.

JOSEPH WIENER, OF PHILADELPHIA, PENNSYLVANIA.

SAFETY-HATPIN.

1,382,039.

Specification of Letters Patent. Patented June 21, 1921.

Application filed October 21, 1920. Serial No. 418,413.

To all whom it may concern:

Be it known that I, JOSEPH WIENER, a citizen of Hungary, residing at Philadelphia, in the county of Philadelphia and 5 State of Pennsylvania, have invented certain new and useful Improvements in Safety-Hatpins; and I do hereby declare the following to be a full, clear, and exact description of the invention, such as will enable 10 others skilled in the art to which it appertains to make and use the same.

The general object of this invention is to provide a hat pin for a lady's hat from which the maximum securing effect can be 15 had; one that will accommodate transverse curvature of the scalp of the wearer and when in operative position will be free from any projections, and one that can be expeditiously applied and disconnected from the 20 hat, and when in operative position, will be prevented from becoming accidentally disconnected and will give a highly ornamental effect; and to these ends, the invention consists in the provision of a hat pin as specified 25 which includes a pair of arcuate shaped pins, each having hat engaging ends so as to engage the crown of a hat at diametrically opposite points, the said pins being arranged in spaced relation and a manipulat- 30 ing member connecting the arcuate shaped pins at one of the ends and a substantially triangular shaped member having openings therein adapted to receive the pins and be carried by said pins and located adjacent the 35 manipulating member and adapted to engage the head of the wearer.

With these and other objects in view as will become more apparent as the description proceeds, the invention consists in certain 40 novel features of construction, combination, and arrangement of parts as will be hereinafter more fully described and claimed.

For a complete understanding of my invention, reference is to be had to the following description and accompanying drawings, in which:—

Figure 1 is a view of a fastener in applied position,

50 Fig. 2 is a perspective view of the fastener removed from the hat.

Referring in detail to the drawings, the numeral 1 indicates as an entirety a fastener constructed from a single length of wire 55 which is bent to form parallel and relatively spaced pins 2 which are arcuately curved

from one of the ends to the other end so as to readily conform to the curvature of a person's head when applied to the hair of a person and to a hat 3 as illustrated in Fig. 1. 60 The single length of wire prior to forming the pins 2 is bent upon itself to form a handle 4 which constitutes a loop and a shank 5. The wire after forming the shank 5 is bent at right angles in opposite directions 65 and then into parallelism to form the pins 2. The runs of wires 5 which form the shank 5 may be secured together by solder or similar material to form a solid shank and one capable of withstanding com- 70 siderable strain. The shank and handle 4 follow out the curvature of the pins 2. Tines 6 are formed on the upper faces of the pins 2 adjacent one of their ends and are curved inwardly and then upwardly and outwardly 75 from the shank 5 and are adapted to engage the crown of the hat 3 at one point while the other ends of the pins engage the crown of the hat at an opposite point and after being passed through the hair on a person's 80 head.

A shield 8 constructed from celluloid or any other material and of substantially triangular shape in outline is provided with spaced openings 9 to receive the pins 2 and 85 is adapted to underlie the shank 5 and handle 4 and engage the sides of a person's head so as to render the device comfortable to the wearer by preventing the shank and handle 90 from pressing against the head.

While I have shown and described the preferred embodiment of my invention, it will be understood that minor changes in construction, combination, and arrangement of parts may be made without departing from 95 the spirit and scope of the invention as claimed.

Having thus described my invention what I claim is:—

1. A hat fastener consisting of a single 100 piece of wire bent upon itself to provide a manipulating member, the opposite ends of the wire being continued from the manipulating member to provide a pair of fastening pin members, and said members being 105 curved longitudinally, a pair of fastening tines formed on the fastening pin members and adapted to bite into the crown of a hat and at one side of the crown of the hat and at a point above the manipulating member, 110 said fastening pin members having their free ends in engagement with the crown of

the hat at diametrically opposite points from the tines.

2. A hat fastener comprising spaced parallel and longitudinally curved pins, a member connecting said pins at one of their ends, a shank formed on said member, a loop handle formed on said shank, said shank and handle forming a continuation of the curve of the pins, tines formed on the connected 5 ends of the pins and being bent inwardly and then outwardly and upwardly to engage the crown of a hat above the handle, said pins adapted to have their other ends engage the crown of the hat.
- 10 3. A hat pin comprising spaced parallel and longitudinally curved pins, a member

connecting one of the ends of said pins together, a handle formed on said member, tines formed on the connected ends of the pins and adapted to engage the crown of a hat, the other ends of said pins adapted to engage the crown of the hat at a diametrically opposite point from the point engaged by the tines, and a shield having openings 20 receiving the pins and underlying the connecting member and the handle.

25 In testimony whereof I affix my signature in presence of two witnesses.

JOSEPH WIENER.

Witnesses:

JOSEF TILL,
JOSEPH TELLER.
